US00D904870S

(12) **United States Design Patent** (10) **Patent No.:** **US D904,870 S**
Sill et al. (45) **Date of Patent:** **** Dec. 15, 2020**

(54) **CLOSEABLE CARTON**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/633,125**

(22) Filed: **Jan. 12, 2018**

Related U.S. Application Data

(60) Continuation-in-part of application No. 29/573,421, filed on Aug. 5, 2016, now abandoned, which is a division of application No. 29/539,525, filed on Sep. 15, 2015, now Pat. No. Des. 774,893, which is a continuation of application No. 29/527,085, filed on May 15, 2015, now Pat. No. Des. 762,113, application No. 29/633,125, which is a continuation-in-part of application No. 29/573,599, filed on Aug. 8, 2016, now abandoned, which is a division of application No. 29/545,302, filed on Nov. 11, 2015, now Pat. No. Des. 774,896, which is a continuation-in-part of application No. 29/527,085, filed on May 15, 2015, now Pat. No. Des. 762,113, application No. 29/633,125, which is a continuation-in-part of application No. 29/604,589, filed on May 18, 2017, now Pat. No. Des. 816,480, which is a division of application No. 29/573,472, filed on Aug. 5, 2016, now Pat. No. Des. 787,314, which is a division of application No. 29/545,297, filed on Nov. 11, 2015, now Pat. No. Des. 786,663, which is a continuation of application No. 29/516,707, filed on Feb. 5, 2015, now Pat. No. Des. 774,891, application No. 29/633,125, which is a continuation of application No. 29/615,117, filed on

OTHER PUBLICATIONS

Notice of Allowance dated Apr. 18, 2016 from U.S. Appl. No. 29/527,085.

Office Action dated Feb. 1, 2016 from U.S. Appl. No. 29/516,707.

Primary Examiner — Rhea Shields

(74) *Attorney, Agent, or Firm* — Forrest Firm, P.C.

(57) **CLAIM**

The ornamental design for a closeable carton, as shown and described.

DESCRIPTION

FIG. 1 is a front perspective view of a first embodiment of the closeable carton, showing our new design. The rear perspective view being a mirror image thereof;

FIG. 2 is a top plan view thereof;

FIG. 3 is a front perspective view of a second embodiment of the closeable carton, the rear perspective view being a mirror image thereof; and,

FIG. 4 is a top plan view thereof.

In the drawings, the broken lines are for the purpose of illustrating portions of the closeable carton that form no part of the claimed design.

1 Claim, 4 Drawing Sheets
